OSCAR M. CARLETON, OF SOMERVILLE, MASSACHUSETTS, ASSIGNEE OF ONE-HALF TO
SILAS W. BENNETT, OF SOMERVILLE, MASSACHUSETTS.

ENVELOP-FEEDING DEVICE.

1,116,992.

Specification of Letters Patent. Patented Nov. 10, 1914.

Application filed December 6, 1913. Serial No. 805,002.

To all whom it may concern:

Be it known that I, OSCAR M. CARLETON, a citizen of the United States, and a resident of Somerville, in the county of Middlesex and Commonwealth of Massachusetts, have invented certain new and useful Improvements in Envelop-Feeding Devices, of which the following is a full, clear, and exact description.

10 While this device may be utilized for feeding envelopes to printing presses and the like, it is specifically designed to be used in conjunction with typewriters for enabling envelopes to be addressed rapidly and 15 exactly.

In the drawings, Figure 1 is a perspective view of an envelop feeder embodying my invention, the same being shown as connected with a visible typewriter. Fig. 2 is 20 a cross section of the same, but with parts thereof folded down upon others. Fig. 3 is a cross section of the device with an envelop shown as just being fed into the engagement of the typewriter rollers. Fig. 25 4 is a perspective view of the resilient arm by which the envelopes are held in place. Fig. 5 is a perspective view of a form of the device adapted for use in connection with an old style typewriter. Fig. 6 is a diagram 30 of the feed rolls and the notched edge of the feeder plate.

My feeding device comprises essentially a shelf 1 upon which the envelopes 2 are stood on edge, with the flaps 3 toward the typewriter roll 4, said shelf being suitably supported, as by the arms 5 attached to the typewriter. To the front edge of the shelf is hinged a frame consisting of grooved uprights 6 and a longitudinal bar 7, the pintles 40 of said hinges 9 being thumb screws 10, whereby the loosening of the latter permits the said frame and the plate 11 carried thereby, to be folded down upon said shelf, while said frame and plate is fixed in the 45 normal position by tightening the thumb-screws. Said plate 11 has its lateral edges slideable in the grooves 12 in said uprights, and is moved up and down therein by the thumb-piece 40 at its top edge. For causing said plate to move without binding in said grooves and to maintain its lower edge perfectly horizontal, a shaft 14 is provided, having its ends supported in bearings 15 on 50 said uprights, and carrying gears 16 meshing with racks 17 fastened on said plate. A

helical spring 19 serves to retain the plate 11 in its uppermost position, and to aid more or less in its upward return.

When the feed plate 11 is pressed downward, its lower edge enters between the flap 3 of the outermost envelop and such envelop, and carries the latter down with it to the juncture of the typewriter rolls 4 and 20, as shown in Fig. 3. I have found, however, that when the lower edge of the feed plate is unbroken, it is practically impossible to cause said rolls to take the envelop away from the feed plate, and the only way it can be done is to take advantage of the fact that in the modern typewriters the roller 20 is not continuous, but is composed of sections spaced upon the shaft 21. Such spaced sections are illustrated at 3 in Fig. 2 of Patent 941,889, for example. The lower edge of the plate 11 is broken to present several dentitions 22 each adapted to enter the space between two roller sections 20 as illustrated in Fig. 6. Hence when the feed plate presses an envelop down between said sections and the roll 4, there is no plate within 30 the parts of the envelop which are gripped by said roll and sections. Consequently when the roll is turned, the envelop is drawn away from said plate and fed to the point to receive the typewritten address.

As shown in Fig. 5, the swinging arm 23, which is pivoted or hinged to the shelf 1 near its rear edge, is located midway of the shelf so that its yielding pressure comes at the midlength of the envelopes 2. This arm 90 is yieldingly pressed against the envelopes by a helical spring 24, as shown in Fig. 4, and by thus having the pressure disposed at the midlength of the envelopes, such portion is caused to belly forward very slightly 95 but enough to make the point of the flap 3 which is outermost project somewhat beyond the surface of its connected envelop, so that when the feed plate 11 descends its denticular edge enters with certainty the 100 space behind the flap. By having the feed plate frame hinged to the shelf, the device can be readily adjusted to fit any make of 105 visible typewriter, since all that needs to be done after screwing the arms 5 to the same is to unloosen the thumb screws 10, slide the feed plate down between the rolls 4, 20, and then tighten up said thumb screws.

In applying this envelop feeder to the old 110

style, or non-visible type of machine, it is necessary to have it swing up and back when the typewriter cylinder is raised. For this purpose, I have the bars 25 of the shelf 1 extended rearwardly and made rigid with uprights 26. The lower ends of these uprights carry a shaft 27 which is rotatively supported by uprights 29, arms 30 and plugs 31 entering the sockets 32 which are provided for the support of the usual paper shielding plate. At one or both ends of the roll or cylinder 4 is a finger 33 resting thereon and rigid with the feed plate frame, so that when said cylinder is swung up and back, the envelop feeder rises with it. See Fig. 5.

While the remainder of the device can be made in the same manner as already described, it can be constructed as shown in Fig. 5, with a shaft 27 rotatably supported in the upper ends of the uprights 26 and having arms 35 rigid therewith. At the extremities of said arms are slots 36 engaging pins 37 projecting from the feed plate 11. A helical spring 38 upon said shaft serves to yieldingly press said plate upward. The plate frame is here shown as rigid with the shelf 1, instead of being hinged thereto as in the other construction.

In the operation of this feeding device, the plate 11 is first adjusted to present its lower edge at the points of contacts of the cylinder 4 and sectional feed roll 20, as above described, since when not in use the said plate is turned flat down upon the shelf 1 in order to render the device more compact. Then the yielding arm 23 is pressed backward and a bunch of envelops introduced between the same and the back of the feeder plate, with the flaps toward the front. The normal position of the feeder plate being immediately above the flap of the outermost envelop, the depression of said plate by the application of the operator's hand to the thumb piece 40, carries the lower edge of said plate into the space between said flap and its envelop and then

forces the plate and envelop down between the cylinder 4 and feed roll 20. The cylinder is then turned and carries such envelop around to the proper impression-receiving position; after which, or even simultaneously therewith, the feeder plate is returned to its normal position.

It should be noted that the feeder device is supported by and slides with the typewriter carriage, so that at all times the device is in proper position relative to the carriage for delivering envelops thereto.

What I claim as my invention is:

1. An envelop feeder comprising a supporting means for the envelops, a feeder plate slidable in its own plane, means pressing the envelops against said plate, a rack at each end of said plate, a horizontal shaft parallel with said plate, and pinions connecting said shaft with said racks, whereby to insure parallel movement of said plate.

2. An envelop feeder comprising a supporting shelf for the envelops, a feeder plate slidable in its own plane, means pressing the envelops against said plate, and a horizontal rotatable shaft having a pinion near each end, said plate having racks meshing with said pinions.

3. The combination with a typewriter having feeder rolls which are interrupted or sectional, of an envelop feeder comprising a supporting shelf, a feeder plate slidable in its own plane, and means pressing the envelops against said plate, the edge of the plate which is designed to engage the feeder rolls being formed with notches disposed to avoid the feeder roll sections, while the edge-portions come between the feeder roll sections.

In testimony that I claim the foregoing invention, I have hereunto set my hand this 4th day of December, 1913.

OSCAR M. CARLETON.
